LADY'S STOCKING

Curt Seifart, Charlotte, and Avery D. May, Shelby, N.C., assignors to Hudson Hosiery Company, Charlotte, N.C., a corporation of North Carolina

Filed Feb. 5, 1965, Ser. No. 83,692

Term of patent 14 years

(Cl. D47—7)

FIG. 2

FIG. 1 is a side elevational view of a lady's stocking incorporating our new design with the opposite side of the stocking being the same as that shown; and

FIG. 2 is a full scale showing of a section of the fabric forming the body of the stocking.

We claim:

The ornamental design for a lady's stocking, as shown and described.
